SMOKER'S PIPE RACK

Jacque Fresco, 3112 SW. 23rd St.,
Miami, Fla. 33142

Filed Mar. 7, 1967, Ser. No. 6,111

Term of patent 14 years

(Cl. D85—8)

FIG. 1

FIG. 1 is a perspective front view of a smoker's pipe rack, showing my new design.

FIG. 2 is a rear perspective view thereof.

FIG. 3 is an end elevation thereof.

The dotted lines shown in FIG. 1 are for illustrative purposes only.

I claim:

The ornamental design for a smoker's pipe rack, as shown and described.
